US00D899926S

(12) **United States Design Patent** (10) **Patent No.:** **US D899,926 S**
(45) **Date of Patent:** **** Oct. 27, 2020**

(54) **BOTTLE CAP**

(71) Applicant: **Microlyses, LLC**, Brooklyn, NY (US)

(72) Inventor: **Rakesh Guduru**, Weston, FL (US)

(73) Assignee: **Microlyses, LLC**, Brooklyn, NY (US)

(**) Term: **15 Years**

(21) Appl. No.: **29/680,920**

(22) Filed: **Feb. 21, 2019**

(51) **LOC (12) Cl. 09-07**

(52) **U.S. Cl.**

USPC **D9/439**

(58) **Field of Classification Search**

USPC D3/201, 202; D7/300, 300.1, 317, 321, D7/391, 392, 392.1, 396.2, 601, 602, D7/619.1, 629; D9/434–436, 439, 440, D9/443, 445–447, 449, 452–454, 499

CPC B65D 51/24

(74) *Attorney, Agent, or Firm* — Weiss & Arons LLP

(57) **CLAIM**

The ornamental design for a bottle cap, as shown and described.

DESCRIPTION

FIG. 1 is a top perspective view of a bottle cap, showing my new design;

FIG. 2 is a bottom perspective view thereof;

FIG. 3 is a front elevation view thereof, the rear, right-side, and left-side elevation views being a mirror image thereof;

FIG. 4 is a top plan view thereof; and,

FIG. 5 is a bottom plan view thereof.

The broken lines depict portions of the bottle cap that form no part of the claim.

1 Claim, 4 Drawing Sheets
